CHARLES H. TRUE, OF HAMMOND, INDIANA, ASSIGNOR TO LOCOMOTIVE SUPERHEATER COMPANY, OF NEW YORK, N. Y., A CORPORATION OF DELAWARE.

MACHINE-TOOL FOR GRINDING SPHERICAL SURFACES.

1,128,918.

Specification of Letters Patent. Patented Feb. 16, 1915.

Application filed May 18, 1914. Serial No. 839,263.

To all whom it may concern:

Be it known that I, CHARLES H. TRUE, residing at Hammond, Lake county, Indiana, have invented a certain useful and Improved Machine-Tool for Grinding Spherical Surfaces, of which the following is a specification.

My invention relates to a machine tool, preferably portable self-contained and motor driven, for use in grinding spherical surfaces quickly and accurately.

While my invention may be applied in the grinding of either convex or concave spherical surfaces, I have, in the preferred form herein disclosed, intended it more particularly for use in grinding the concave spherical surfaces in superheater headers or steam collectors, as they are often called, which receive similarly formed ends of superheater elements, and which constitute the outer ends of the several openings into the header, through which steam is passed to and from said elements. Superheater elements connected to the header in this way are spoken of as having "ball and joint" connection. Joints of this kind are shown, for example, in the patent to Cole and Hoffmann, No. 1,054,676, of March 4, 1913.

It is the object of my invention to provide a machine tool of the character specified which may be readily applied to the header and preferably moved from point to point where the spherical surfaces are to be ground.

A further object of my invention is to provide a simple and compact tool of the character specified which shall grind the spherical surfaces automatically and accurately and with little if any attention on the part of an attendant after the tool has been placed in position.

A still further object of my invention is to provide a machine tool of the character specified which shall operate uniformly and produce uniform results.

Further objects of my invention will appear as the specification proceeds.

My invention resides in certain details of construction and arrangement, and will be better understood by referring to the accompanying drawing which illustrates a central longitudinal section, partly in elevation, of a preferred form of the invention.

Referring to the drawing, the heavy metal base 1, the lower surface of which is machined accurately flat, is provided with an

overhead, rigid standard or bracket 2. Mounted above the base is an air motor 3 having an extended shaft 4, the two ends of which are journaled respectively in the base 60 and in the bracket 2. Shaft 4 has a spur gear 5 fixed thereto and meshing with a second spur gear 6, of considerably greater diameter, which is rotatably mounted upon the lower end of a fixed shaft 7 carried at the 65 outer end of the bracket 2. Near the periphery of gear 6 is a boss 8, counterbored to receive a rotatable spindle 9 carrying at its end, on the upper side of the boss, a small bevel spur gear 10, and at its lower extremity connecting to a sleeve 11 by a preferably universal joint 12. The axis of spindle 9 is inclined inwardly and downwardly so as to intersect the axis of shaft 7 just above the plane of the lower surface of base 1. A 70 bevel gear 13 is fixed, so that it cannot rotate, upon the shaft 7 just above the gear 6 and its diameter is such as to mesh with bevel gear 10.

A spindle 14 is accurately but slidably fitted within the sleeve 11 and provided with a key 15 projecting through a slot 16 in said sleeve; this permits the spindle to slide up and down in the sleeve but compels it to rotate therewith. At the lower end of 80 spindle 14 is the grinding element 17, the extreme tip of which is convexed spherically, and mounted upon the spindle above this grinding element is weight 18. A flat sheet metal gage 19 the lower surface of 85 which is substantially flush with the lower surface of base 1, is fixed to said base and provided with a hole 20, the center of which lies in the axis of gear 6. The diameter of this hole is slightly greater than the diameter 90 of the spherical surface which is to be ground.

In operation the machine is placed upon the previously machined surface of the header in which are the openings whose outer ends are to be provided with spherically formed surfaces. These openings will have been made in any suitable manner, preferably by drilling, counterboring and then roughly countersinking their outer 100 ends. The machine should be so set that the center of hole 20 will correspond with the center of the, to be formed, spherical surface. The motor is now started and gear 5 will rotate gear 6 so as to roll bevel gear 10 upon the periphery of gear 13. This will cause a corresponding rotation of the grind-

ing element 17 in the countersunk end of the header opening. As the grinding element rotates about spindle 14, the shaft itself will describe a conical surface of revolution about the point at which its axis intersects the axis of gear 6. During the grinding operation the spindle 14 will rise and fall in sleeve 11 in correspondence with any inequality of the surface which is being ground and in accordance with any variation in the rate of grinding due to varying decrease of hardness of the metal itself.

The weight 18 should be suitably selected so as to cause the metal to be ground away 15 at a convenient rate.

While I have shown my invention driven by an air motor it is obvious that a gasolene or electric motor or any other desired form of motor might be substituted therefor.

20 When a sufficient amount of material has been ground away so as to leave a satisfactory spherical surface, the motor is stopped and the machine lifted and moved to a point where a second surface is to be 25 ground and so on until all of the desired spherical surfaces are formed.

Instead of stopping the machine by cutting off the source of power by hand operated switch or the like, I may, of course, arrange 30 to have it stopped automatically by any known form of automatic stop device, of which there are many.

Instead of embodying my invention in a self-contained operable machine as above 35 described, I may, if I prefer, omit the motor altogether and drive gear 6 from any separate and usual source of power by a belt chain or other suitable device.

When the machine is not in use, the 40 grinding element and its operating shaft, etc., may be raised about the universal joint and placed in the metal holding loop or hook 21, which is fixed to the bottom of gear 6 diametrically opposite spindle 9.

45 Other changes of detail may be made within the scope of my invention as defined by the following claims.

I claim:

1. In a tool for grinding spherical surfaces, an inclined shaft, a spherically tipped grinding element flexibly joined to said shaft, and means for rotating said shaft upon its axis and at the same time causing said axis to describe a conical surface of revolution about an axis which will pass substantially through the center of said tip.

2. In a grinding tool, a spindle, a shaft 60 flexibly joined to one end of the spindle, a grinding element fixed upon the other end of said spindle and arranged to be supported upon the work to be ground, and means for rotating said shaft upon its axis and at the same time causing said axis to describe

a surface of revolution about an axis which will pass substantially through the center 65 of said grinding element.

3. In a tool for grinding spherical surfaces the combination of a shaft having a fixed axis, a shaft having an axis inclined thereto, a grinding element flexibly joined to said inclined shaft, and means operatively relating said two shafts for causing the axis of said inclined shaft to simultaneously describe a conical surface of revolution about the axis of the fixed shaft and to 75 rotate about its own axis.

4. In a tool for grinding spherical surfaces the combination of a main gear, a second gear meshing therewith, a shaft for said second gear having its axis intersecting 80 the axis of the main gear, a grinding element carried by said shaft, and means for rotating said shaft so as to describe a conical surface of revolution about the axis of the main gear.

5. In a tool for grinding spherical surfaces the combination of a pair of meshed gears having intersecting axes, a shaft fixed to one of said gears, a spherical grinding element flexibly united to said shaft and 90 having its center substantially coincident with the point of intersection of the two axes, and means for moving said shaft so that its axis will describe a conical surface of revolution about the other axis.

6. In a tool for grinding spherical surfaces, the combination of a fixed and a rotatable gear having a common axis, an outer gear carried by said rotatable gear and meshing with said fixed gear, the axis 100 of said outer gear intersecting the axis of the first named two gears, a grinding element attached to and arranged to rotate with said outer gear and a driving gear meshing with said rotatable gear.

7. A tool for grinding spherical surfaces, comprising a downwardly inclined spindle having a grinding element at its lower end and a universal joint at its upper end, whereby the grinding element is normally 110 partially supported by the work to be ground and is lowered with the progress of the grinding, and means for rotating said grinding element upon said spindle while at the same time causing the axis of said spindle to describe a conical surface of revolution about an axis passing through said grinding element.

In testimony whereof I have hereunto set my hand in the presence of two subscribing 120 witnesses.

CHARLES H. TRUE.
